UNITED STATES PATENT OFFICE.

CHESTER A. HULL, OF PERU, INDIANA, ASSIGNOR TO RICHARD H. CHAMBERLAIN AND
THOMAS A. KEYES, BOTH OF PERU, INDIANA.

HANDLE-WRAPPING MACHINE.

Specification of Letters Patent. Patented Apr. 11, 1922.

1,412,747.

Application filed May 9, 1921. Serial No. 467,852.

To all whom it may concern:

Be it known that I, CHESTER A. HULL, a citizen of the United States, residing at Peru, in the county of Miami and State of

5 Indiana, have invented certain new and useful Improvements in Handle-Wrapping Machines; and I do declare the following to be a full, clear, and exact description of the invention, such as will enable others skilled 10 in the art to which it appertains to make and use the same.

This invention relates to an improved wrapping machine for winding a binding strip upon a handle used in connection with strip upon a handle used in connection with 15 a basket, it being understood however that the machine can be used for wrapping a binding strip upon any article of a similar nature which can be fed longitudinally through a hollow drum in timed relation to 20 the rotation of the drum so that as the drum rotates, the strip of binding material will be wound in a spiral about the article.

One object of the invention is to provide 25 an improved type of drum having an improved construction whereby the strip of material may be wound upon the drum during rotation thereof and at the same time, the inner end portion of the strip caused to feed into the central opening of the drum 30 through which the article to be wrapped passes, to have the strip of material wound about the same as the drum rotates.

Another object of the invention is to so 35 construct the drum that the strip of binding material may have movement independent of the rotation of the drum and thus permitting of a drag feed as the drum rotates to wind the strip of material upon the article.

Another object of the invention is to provide 40 means for placing the strip of material wound upon the article under tension and thus keeping the portion wound tightly upon the article to be bound.

Another object of the invention is to provide 45 a drum so constructed that the strip of binding material may be passed through one of the side disks of the drum into the proper position for engagement by the tensioning means and for winding upon the 50 drum as the drum rotates.

Another object of the invention is to provide 55 improved means for rotatably mounting the drum.

Another object of the invention is to provide 60 means for feeding the article through

the drum, this feeding means including a toothed roller mounted upon a shaft which may be moved into and out of an operative position.

Another object of the invention is to provide 65 improved means for placing a securing tack in the binding strip after the article has been bound and improved means for cutting off the strip after being secured.

Another object of the invention is to provide 70 a device which will be very easy to operate and which will be so constructed that the strip of binding material will be easily wrapped upon the handle or other article.

This invention is illustrated in the accompanying drawings, wherein:

Figure 1 is a view showing the improved machine in side elevation.

Figure 2 is a front elevation of the im- 75 proved machine.

Figure 3 is a top plan view of the im- 80 proved machine.

Figure 4 is a fragmentary view showing the drive element of the feeding mechanism moved to an inoperative position.

Figure 5 is a sectional view taken along the line 5—5 of Fig. 2.

Figure 6 is a sectional view taken along the line 6—6 of Fig. 5.

Figure 7 is a sectional view taken along the line 7—7 of Fig. 5.

This improved binding machine which is used for placing a wrapping upon the handle of a basket is provided with a frame 90 having side members 1 and 2, each of which is U-shaped as shown in Fig. 1 and has its depending standards connected by a cross bar 3, the cross bars carrying bearings to rotatably mount the drive shaft 4 which will 95 be rotated in any suitable manner. In the present illustration, there has been provided a pulley 5 about which a belt 6 will pass but as previously stated, it is to be understood that any suitable means could be substituted 100 for the pulley and belt shown. The side members of the frame are connected by cross strips 7 so that the side members will be securely braced and held in the proper spaced relation.

The drum or strip carrier is provided with a hub 8 which is hollow as shown in Fig. 6 and provided with a clamping ring 9 which is secured to the hub by securing bolts or rivets 10 and provide a circumferentially 110

extending channel or seat in which a sprocket wheel 11 is positioned and secured by the fasteners 10. This sprocket wheel is engaged by the sprocket chain 12 which also passes about the sprocket wheel 13 of the shaft 4 and it will be readily seen that when the shaft 4 is rotated, rotary movement will be transmitted to this hub 8. A bearing ring 14 is carried by supporting strips 15 secured to the upper cross bar of the side member 1 and this bearing ring extends through the clamping ring 9 and has a disk or ring 16 secured to its inner end by securing bolts 17. It will thus be seen that the hub of the carrier will be rotatably mounted upon this bearing ring 14 but that when desired, it may be removed by releasing the nuts of the securing bolts 17 so that these bolts can be removed. Brackets 18 are secured to the outer face of the bearing ring by certain of the securing bolts 17 and have upper and lower bearing arms extending into the interior of the ring as shown in Fig. 6 so that guide rollers 19 may be rotatably mounted in a vertical position within this bearing ring as shown in Figs. 5 and 6. Relatively large disks 20 and 21 are secured to the sides of the hub by fasteners 22 which in addition to mounting the disks 20 and 21 will also serve to rotatably mount rollers 23 as shown clearly in Fig. 7.

When the drum is being rotated to cause the strip of binding material 24 to be wound about the rollers 23 and wound upon the handle 25 with which the inner end of the strip 24 will be connected, it is desired to have this handle fed through the drum and between the guiding rollers 19. There has therefore been provided an outer guiding roller 26 which is rotatably connected with the upper end of the side member 2 by means of a pivot bolt 27 which passes through an opening formed in the side extension 28 of this side member 2. There has also been provided a feeding roller 29 having a toothed head 29' for engaging the handle and feeding the handle between the rollers when this feeding roller 29 rotates. This feeding roller is mounted upon the upper end of the shaft 30 which shaft extends through a slot 31 formed in the side extension of the side member 2. The lower end of the shaft 30 which may be termed a driven shaft, is rotatably mounted by means of a bearing 32 and carries a worm-gear 33 which meshes with a worm carried by the driving shaft 4. It will thus be seen that when the shaft 4 is rotating, rotary movement will be transmitted to the driven shaft 30 and when the shaft 30 is in the vertical position shown in Fig. 1, the teeth of the roller 29 will engage the handle and force the handle longitudinally through the drum. This shaft 30 is permitted of swinging movement so that it can be drawn to the inoperative position of Fig. 4

when it is desired to stop feeding of the handle. In order to permit the shaft to be readily drawn to the inoperative position against the action of the spring 34, which normally holds it in the operative position, there has been provided a strip 35 which is loosely mounted upon the shaft and passes through a loop 36. This strip 35 is provided with a side notch as shown at 37 so that when the shaft has been drawn to the inoperative position of Fig. 4, this strip 35 may be swung to engage the guiding strip 36 and thus provide a latch element. As soon as it is desired to have the handle feed through the hub again, it is simply necessary to swing the latch to the position of Fig. 3 and the spring will return the shaft to the operative position as shown in this figure.

When this device is in use, the strip of binding material will be led from a source of supply and passed through the eye 38 of the guide 39 and will then be passed through the slot 40 provided in the outer disk 21. The handle will first have been passed through the hollow hub and will be in position to receive the end of the binding strip which will first however be passed between the blocks 41 and 42 carried by a strip 43 secured to the inner disk 20. The block 42 is pivotally mounted and engaged by a spring 44 so that it will be yieldably held in engagement with the block 41 and will thus provide pressure against the binding strip to hold the portion of the strip wrapped about the handle under tension. When the binding strip has been passed through the tensioning means and connected with the handle, the shaft 4 can be rotated and rotary movement will be transmitted to the drum. As the drum rotates, the binding strip will be wound upon the drum about the rollers 23 and at the same time, the inner end portion of the strip will be drawn inwardly off of the drum and carried about the handle so that it is wound upon the handle. During rotation of the drum to wind the strip upon the handle, the handle will be moved longitudinally through the open central portion of the drum and therefore the strip will be wound upon the handle in a spiral so that the handle will be neatly wrapped and completely covered by the strip of binding material. This binding material is wrapped loosely upon the spool or other source of supply and therefore when the inner end portion is drawn upon the strip will not bind and tear. The fact that the strip is wound about rollers will also permit of it being readily drawn into the interior of the hub. The friction blocks or tensioning blocks 41 and 42 will hold the portion of the strip wound about the handle under proper tension and therefore a close and neat binding will be provided for the handle. After the strip of binding has been wound

upon the handle as much as desired, the strip should be secured to the handle. There has therefore been provided a plunger 45 which extends through an opening formed in the hub 8 and is provided with a cross pin 46 engaging a spring 47 so that the plunger or hammer 45 will be normally held in an inoperative position. This plunger is formed of magnetized metal so that when a tack 5 of the strip passes through the plunger 45 it will be held in proper position to be driven into the handle when the plunger is moved inwardly by the operating lever 48 which is pivotally mounted upon the bearing bar 49. It is also desired to permit the strip to be readily cut off close to the point where the tack passes through the strip and therefore there has been provided a cutting plunger 50 which is also slidably passed 10 through an opening formed in the hub 8 and provided with an abutment engaging a spring 51 for drawing the plunger 50 to an inoperative position. From an inspection of Fig. 1, it will be readily seen that when the lever 48 is swung to move the hammer 45 inwardly, it will not engage the cutting plunger or chisel 50. If it is desired to cut the strip a plunger 52 which is 15 slidably connected with the lever 48 by brackets or guides 53 will be moved downwardly against the action of the spring 54 so that its head 55 will be brought into position to engage the outer end of the plunger 50. Therefore, when desired, the plunger 50 can be forced inwardly to cut 20 the binding strip close to the tack which has been previously forced into the handle by means of the plunger 45. There has thus been provided a handle wrapping device which is easy to operate and which is 25 very efficient in operation and which will wrap a handle with the wrapping neatly applied and firmly held in place.

I claim:

- 45 1. A wrapping machine comprising a rotatable carrier for receiving a strip of wrapping material from a source of supply, the carrier being provided with an opening, means for feeding an article through the opening axially of the carrier, means for rotating the carrier to wind a strip of wrapping material thereon with the inner end portion of the strip winding upon the article as the carrier rotates, and means 50 for engaging the strip of binding material between the article and carrier to place under tension the portion of the strip wound upon the article.
- 55 2. A wrapping machine of the character described comprising a rotatable drum having a central opening, means for supporting an article to be wrapped with the article extending through the central opening of the drum, means for rotating said drum to 60 wind a strip of binding material upon the 65
- drum with the inner end portion winding upon the article as the drum rotates, means carried by the drum and extending into the central opening for engaging the strip of binding material and placing tension thereon as it is wound upon the article, and means for feeding the article through the drum in timed relation to the rotation of the drum.
- 70 3. A wrapping machine of the character described comprising a rotatable drum open at its center and having spaced side disks and rollers rotatably mounted between the side disks, means for holding an article to be wrapped with the article extending 75 through the central opening of the drum, means for feeding the article through the drum, and means for rotating the drum to wind a strip of binding upon the drum about the rollers and cause the inner end 80 portion of the strip to be wound upon the article as fed through the drum, means for applying tension to the portion of the strip wrapped about the article, means for applying a fastener while the binding strip is 85 held under tension, and means for severing the binding strip after being secured to the article.
- 90 4. The structure of claim 2 having the tensioning means consisting of an arm carried by the drum and extending into the control opening of the drum, and means carried by said arm for engaging the strip between the drum and article for applying tension to the portion of the strip wound 95 upon the article as fed through the drum.
- 100 5. A machine of the character described comprising a drum provided with a hollow hub block, disks arranged to one side of said hub block and in spaced relation to each other, rollers rotatably mounted between said disks, a sprocket wheel fitting against the opposite side of the hub block, a clamping disk fitting against the sprocket wheel and having an annular flange extending into the hub block, means for rotatably mounting the drum including a bearing sleeve positioned within the flange of the clamping disk and having an outstanding 110 collar engaging the clamping disk and a 115 ring secured to the inner end of the sleeve and holding the hub block upon the sleeve, means for holding an article to be wrapped with the article extending through the hollow hub block, means for feeding the 120 article through the hub block, and means for rotating the drum to wind a strip of binding upon the drum about the rollers and cause the inner end portion of the strip to be wound upon the article as fed through 125 the hub block.
- 130 6. In a wrapping machine, article carrying and feeding means, means for wrapping a strip of wrapping material about the article as fed, means for applying a

fastener to hold the strip in place upon the article, and means to sever the strip after being secured.

7. In a wrapping machine, article carrying and feeding means, means for wrapping a strip of wrapping material about the articles as fed, means for applying tension to the portion of the strip wrapped about the article, and means for applying a fastener while the strip is held under tension.

8. In a wrapping machine, article carrying and feeding means, means for wrapping a strip of wrapping material about the article as fed, means for applying a fastener to hold the strip in place upon the article, means to sever the strip after being secured, and common operating means for the fastener applying means and strip severing means movably mounted and operating the fastener applying means when in-

itially moved, further movement of the operating means after operating the fastener applying means operating the strip severing means.

9. The structure of claim 8 having the cutting means and fastener placing means in the form of plungers carried by said drum, and operating means for the plungers consisting of a lever for engaging the fastener placing plunger to force the same to an operative position, and an abutment element movably carried by said lever for engaging the cutting plunger and moving the same to an operative position when the lever is moved toward the plungers with the abutment element moved to an operative position.

In testimony whereof I have hereunto set my hand.

CHESTER A. HULL.
